UNITED STATES PATENT OFFICE.

JOHN W. KELLY, OF MINNEAPOLIS, MINNESOTA.

SWITCH-BOARD.

SPECIFICATION forming part of Letters Patent No. 399,269, dated March 12, 1889.

Application filed March 13, 1888. Serial No. 267,129. (No model.)

To all whom it may concern:

Be it known that I, JOHN W. KELLY, a citizen of the United States, and a resident of the city of Minneapolis, county of Hennepin, State 5 of Minnesota, have invented a certain new and useful Switch-Board for Electric-Light Stations, of which the following is a specification, reference being had to the accompanying drawings.

- 10 My invention was designed more especially for use in electric-light stations, and it has for its object to provide a switch-board which will afford a convenient means of connecting several dynamos to the same lamp-circuit, or 15 of cutting out one dynamo and throwing in another without stopping the lights, or of connecting together several lamp-circuits through one dynamo or the several dynamos and the several lamp-circuits.
- 20 My invention consists of the construction hereinafter fully described, and particularly pointed out in the claim.

In the drawings, like letters referring to like parts throughout, Figures 1, 2, and 3 are front 25 elevations of my switch-board, and Fig. 4 is a rear elevation of the same.

A is a slab of non-conducting material—such as wood—preferably rectangular and oblong in shape.

30 B B' and C C' are pairs of parallel metallic strips constituting parts of the conductors b b' and c c' from two independent dynamos. (Not shown.)

D D' and E E' are parts of pairs of conductors constituting independent circuits through sets of electric lamps. (Not shown.)

F F' are independent sets of binding-posts projecting through the slab A from back to front, to which, on the rear of the board, the 40 lamp-circuit conductors are connected, the positive wire of each circuit being connected to one set of binding-posts, as D to F, and the negative wire of each circuit connected to the other set of binding-posts, as D' to F', respectively.

It should be further noted that these positive and negative sets of binding-posts are on the opposite sides of the dynamo-circuits.

G G' are an independent set of binding-50 posts, positive and negative, respectively, passing through the slab A, and connected,

respectively, at the back of the board to the positive and negative conductors of the lamp-circuits. These binding-posts are preferably arranged in line at one end of the board and 55 are provided on their face ends with means, as an eyelet, for the ready attachment of a cable or loop wire, H, for coupling lamp-circuits.

It should be further noted that the lamp-conductors and the dynamo-conductors cross each other. It is preferable to have them cross each other at right angles, though it is not necessary that the angle should be at a right angle.

To the face ends of the binding-posts F F' are pivoted the customary contact-strips, K K', with finger-pieces of hard rubber.

L L' are positive and negative binding-posts attached at the back of the slab, respectively, to the positive and negative dynamo-conductors and projecting through the board with their outer or face ends above the same in the proper position to be reached by the free ends of the contact-strips K and K', 75 respectively.

M are small stops in the face of the board in the proper position to limit the movement of the contact-strips K K' and prevent accidental contacts.

N are wooden strips projecting from the back of the board between all the wires of the lamp-circuits for the better prevention of accidental contacts.

The operation of the board is illustrated in 85 Figs. 1, 2, and 3, attention being directed to the full and dotted line positions of the pivoted contact-strips and the cable H. The cable H not being used and the pairs of pivoted contacts being in the position shown 90 in Fig. 1, the independent dynamos will be connected each to an independent lamp-circuit. If the cable be not used and the pivoted contacts be in the full-line position shown in Fig. 2, both dynamos will be on the one 95 lamp-circuit D D'. If the cable be thrown in and the pivotal contacts be in the positions as shown in Fig. 3, all the lamps will be coupled to a single dynamo, while if the pivoted contacts on the left be in the full-line 100 positions and the pivoted contacts on the right be in the dotted-line positions and the

cable be used as shown in Fig. 3, all the lamps and all the dynamos will be thrown into a single continuous circuit.

The board, as shown, represents the arrangement of the conductors and connections for two dynamos and two sets of lamps. It is evident, however, that the principle would be the same for an indefinite number. All that is necessary is to extend the board sidewise and lengthwise and multiply the lamp and dynamo conductors, the binding-posts, and pivoted contacts. In so doing the essentials are to make all the lamp-wires cross all the dynamo-wires, to have a positive binding-post for every positive lamp-wire protruding through the switch-board adjacent to every positive dynamo-wire, a negative binding-post from every negative lamp-wire adjacent to every negative dynamo-wire, corresponding positive and negative contact-points protruding from the dynamo-wires, the requisite pivoted contact-strips for connecting the lamp and dynamo binding-posts, an independent set of positive and negative binding-posts projecting through the board from the various positive and negative lamp-wires, and a cable for coupling the same together. This last feature is only necessary in order to make the board universal for the purpose of connecting two or more of the lamp-circuits together into one circuit through one or more of the dynamos. Any one or all of the dynamos whose conductors are crossed by the conductors of a given lamp-circuit may be thrown onto that particular lamp-circuit without the use of any cable, and where several different dynamos and several different lamp-circuits are used it is evident that all ordinary requirements in the way of re-enforcement of dynamos or substitution of dynamos may be made without the use of any cable.

This board is a great convenience in electric-light stations, where it is often desirable to substitute one dynamo for another. Hitherto it has been difficult to do this without putting out the lights. It is evident that this substitution can be readily effected by my de-

vice. The substitute dynamo may be coupled onto the lamp-circuit in multiple with the old one for a moment and then the old one taken off. It is capable of a wide diversity of other uses, both in electric-light stations and in other places, as is evident from the previously-described constructions.

While dynamos are spoken of throughout the specification and lamps as the points of distribution or use, it will of course be understood that these terms are not words of limitation, but merely words of illustrative use. The conductors b b' and c c' are intended, broadly, as source conductors and the wires D D' and E E' as distribution-conductors, taking the electricity wherever required for any kind of use.

What I claim, and desire to secure by Letters Patent of the United States, is as follows:

In a switch-board, the combination, with two or more sets of source conductors, as b b' and c c' , of two or more sets of distributing-conductors, as D D' and E E' , crossing said source conductors on the switch-board, sets of binding posts or contacts, as L L' , projecting from said source conductors through the face of the board corresponding in number on each set of source conductors to the sets of distributing-conductors, sets of binding posts or contacts, as F F' , projecting from said distributing-conductors through the face of the board in proximity to the sets of said source contacts corresponding in number on each set of distributing-conductors to the sets of source-conductors, pivoted contacts, as K K' , adapted to connect L L' and F F' , or such of them as desired, an independent series of binding posts or contacts, as G G' , attached to and corresponding in number to the distributing-conductors, and a removable cable, H , adapted to connect any set of the same together, substantially as described.

JOHN W. KELLY.
